CLAIM

The ornamental design for pen and note holder, as shown and described.

DESCRIPTION

FIG. 1 is a perspective view of a pen and note holder showing our new design;

FIG. 2 is a top plan view of the pen and note holder of FIG. 1;

FIG. 3 is a front elevational view of the pen and note holder of FIG. 1;

FIG. 4 is a right side elevational view of the pen and note holder of FIG. 1, the left side elevational view being a mirror image thereof;

FIG. 5 is a rear elevational view of the pen and note holder of FIG. 1;

FIG. 6 is a bottom plan view of the pen and note holder of FIG. 1;

FIG. 7 is a perspective view of the pen and note holder of FIG. 1, showing a pen holding portion in an open position;

FIG. 8 is a top plan view of the pen and note holder of FIG. 7; and,

FIG. 9 is a right side elevational view of the pen and note holder of FIG. 7, the left side elevational view being a mirror image thereof.
